UNITED STATES PATENT OFFICE.

AUGUST E. KLINGER, OF TONAWANDA, AND FREDERICK C. BURKHARDT, OF BUFFALO, NEW YORK, ASSIGNEES TO BUFFALO STEEL COMPANY, OF TONAWANDA, NEW YORK, A CORPORATION OF NEW YORK, AND THE CROSBY COMPANY, OF BUFFALO, NEW YORK, A CORPORATION OF NEW YORK.

CHAIR FOR CONCRETE-REENFORCING RODS.

Application filed May 31, 1924. Serial No. 717,082.

This invention relates to a chair which is more particularly designed for supporting rods or bars used in reenforcing concrete pavements, although the same may also be used in other installations where similar conditions exist, for instance in laying a concrete floor of a building which is to be reenforced with metal rods or bars.

It is the object of this invention to provide a chair of this character which is comparatively simple in construction, which can be produced at low cost and which can be readily and conveniently used for reliably supporting the reenforcing rods in various numbers and in different angular relation to each other as well as permitting of supporting a plurality of sets of such rods or bars one above the other.

In the accompanying drawings:

Figure 1 is a top plan view showing a reinforcement for a concrete pavement floor or the like made up of a plurality of bars arranged at right angles to each other and supported by chairs embodying our improvements.

Figure 2 is a perspective view of a chair constructed in accordance with our invention and showing a pair of lower and a pair of upper reenforcing rods or bars mounted on this chair.

Figure 3 is a side elevation of this improved chair showing the condition of the same before the reenforcing rods or bars are mounted thereon.

Figure 4 is a front elevation thereof.

Figure 5 is a vertical longitudinal section, taken on line 5—5, Figure 4.

Figure 6 is a top plan view of this chair.

Figure 7 is a fragmentary side elevation of the lower part of the chair, showing the manner in which two reenforcing rods are mounted on this chair in the position at right angles to each other.

Similar characters of reference indicate like parts in the corresponding views.

Although this chair may be variously constructed for the purpose of supporting reenforcing rods or bars in a variety of ways best suited for the particular job of concrete which is to be reenforced, the particular construction of chair which is shown in the drawings is designed to support an upper and a lower set of rods or bars one above the

other, the lower set in this particular instance comprising lower and upper rods 10 and 11 which are so arranged that an upper rod of each lower set crosses an adjacent lower rod of the same set at right angles thereto, and the upper set also being composed of a plurality of lower rods 12, and a plurality of upper rods or bars 13, each of which crosses one of the lower rods of the upper set at right angles thereto. Each crossing between two adjacent rods of the upper set is arranged vertically in line with a crossing between two bars of a lower set and at these companion crossings between the two pairs of bars of an upper and lower set of such rods, these rods are supported by a chair which embodies our invention and which in its preferred form is constructed as follows:

The numeral 14 represents a horizontal flat base which is adapted to rest upon the foundation of the road which is to be covered with a concrete pavement or the bottom of a cellar or other surface which is to be covered over with concrete. Projecting upwardly from one end of this base is a standard which is generally of channel shaped or U form in horizontal section and comprises an upright transverse web 15 which is connected at its lower end by a downwardly widening portion 19 with the front end of the base 14, and two upright longitudinal flanges 16 which project inwardly from opposite vertical edges of the web 15 and each of which merges at its lower end by means of a curved and downwardly narrowing portion 17 into the transverse front portion of the base 14.

Adjacent to its lower end the web of the standard has a lip 18 stamped outwardly from the stock of this web so that the lower end of this lip remains attached to the web while the upper end thereof is disconnected therefrom. Adjacent to the lip 18 the front edges of the side flanges 16 of the standard are provided with upwardly opening notches 20 which together with the inner side of the respective lip 18 are adapted to form a seat for one of the lower transverse reenforcing rods 10 of the lower set of rods. This rod 10 is engaged with this seat while the lip 18 is in an outwardly bent position, as shown in Figures 3, 4 and 5, and after

this rod is inserted in this seat it is confined therein by bending the upper end of the lip 18 inwardly and over the upper side of the rod 10 and between the adjacent parts 5 of the longitudinal flanges 16 of the standard, as shown in Figures 2 and 7. The removal of the stock from the lower part of the web of the standard by the formation of the lip 18 produces an opening in this 10 web above this lip which opening, if desired, may be further increased by bending that portion of the web of the standard immediately above the lower lip 18 outwardly so as to form an upper lip 21. Through this 15 opening is passed one of the longitudinal upper reenforcing rods or bars 11 of the lower set so that this rod rests on top of the lower lip 18 after the same has been bent over the rod 10. The upper rod 11 is arranged 20 between the side flanges 16 of the standard and is held against displacement thereon by bending the lip 21 downwardly against the upper side of the rod 11 after the parts have been assembled, as shown in 25 Figures 2 and 7. Adjacent to its upper end the web 15 of the standard has another upwardly projecting lip 22 bent outwardly therefrom so that this lip remains attached at its lower end to the web while its upper 30 end is detached therefrom, and adjacent portions of the front edges of the flanges 16 are provided with notches 23 which together with the lip 22 form a transverse seat. This seat is adapted to receive one of the lower 35 transverse rods or bars 12 of the upper set which rod after being engaged with this seat is retained therein by bending the upwardly projecting lip 22 inwardly and over the top of the rod 12 and between the adjacent parts 40 of the side flanges 16, as shown in Figures 1 and 2.

The removal of the stock from the upper front part of the web 15 in the formation of the upwardly projecting upper lip 22 forms 45 an opening between the side flanges 16 immediately above the lip 22. Into this opening is placed one of the longitudinal reenforcing rods or bars 13 of the upper set so that the same rests with its underside on 50 top of the lip 22 and is confined between the upper parts of the flanges 16. Displacement of this upper rod 13 from this position is prevented by bending the upper ends 24, 24 of the flanges 16 inwardly and downwardly 55 into engagement with the top of the rod 13 from opposite sides thereof, as shown in Figures 1 and 2.

When the several chairs are thus connected with the upper and lower sets of re-enforcing bars or rods, the same are reliably held in their proper relative position which they should occupy in the mass of concrete which is subsequently poured over the same to completely embed the chairs and re-enforcing rods.

In the manufacture of these chairs each one is constructed from a single piece of sheet metal of a width equal to the width of the base, this piece being left in its full width condition at one end to form the base 70 portion of the chair and form a bearing contact for the chair on the foundation which is of comparatively large area, while the opposite end of the sheet metal blank, from which the chair is constructed, is bent upwardly and into channel shape and the openings and retaining lips are cut and bent out of the web thereof and the upper ends of the flanges so that practically all of the metal originally present in the blank is 80 utilized in the finished chair, the only waste consisting of the metal which is removed from the side flanges in the formation of the notches 20 and 23.

Owing to the simplicity in the construction of this chair and the ease with which the same can be manufactured, it is possible to produce the same at comparatively low cost.

Furthermore, this chair owing to its one piece construction avoids the use of any separate parts, such as bolts, rivets, or clips for attaching the reenforcing rods or bars thereto, thereby facilitating the mounting of the reenforcing rods or bars thereon and 95 also avoiding loss of parts.

Although the drawings represent this chair as used in connection with reenforcing rods or bars which are round in cross section, obviously this chair is capable of use 100 in connection with any other form of re-enforcing rods or bars such as those now commonly used for reenforcing concrete.

We claim as our invention:

1. A chair for supporting a concrete re-enforcing rod comprising a horizontal flat base, and a standard rising from said base and having an upright web connected at its lower end with one end of the base and upright flanges arranged on opposite vertical edges of said web thereby forming a standard which is U-shaped in horizontal section, and said web having a seat upon which a reenforcing rod is adapted to rest.

2. A chair for supporting a concrete re-enforcing rod comprising a horizontal flat base, and a standard rising from said base and having an upright web connected at its lower end with one end of the base and upright flanges arranged on opposite vertical edges of said web, and said web having a seat upon which a reenforcing rod is adapted to rest, and each of said flanges merging at its lower end into the adjacent end of said base.

3. A chair for supporting a concrete re-enforcing rod comprising a horizontal flat base, and a standard of channel form in horizontal section rising from said base and having a lip struck out of its web which pro-

jects upwardly and is adapted to form a seat for a rod and to be bent with its upper end against the same for confining it thereon.

4. A chair for supporting a concrete reinforcing rod comprising a horizontal flat base, and a standard of channel form in horizontal section rising from said base and having a lip struck out of its web which projects upwardly and is adapted to form a seat for a rod and to be bent with its upper end against the same for confining it thereon, and the parts of the flanges adjacent to said lip being provided with notches which receive the rod resting on said lip.

15 5. A chair for supporting a concrete reinforcing rod comprising a horizontal flat base, and a standard of channel form in horizontal section rising from said base and having a lip struck out of its web which projects upwardly and is adapted to form a seat for a rod and to be bent with its upper end against the same for confining it thereon, the opening formed in said web by the deflection of the stock of said lip being adapted to receive a reenforcing rod at right angles to the first mentioned rod.

6. A chair for supporting a concrete reinforcing rod comprising a horizontal flat base, and a standard of channel form in horizontal section rising from said base and having a lip struck out of its web which projects upwardly and is adapted to form a seat for a rod and to be bent with its upper end against the same for confining it thereon, the opening formed in said web by the deflection of the stock of said lip being adapted to receive a reenforcing rod at right angles to the first mentioned rod, and the upper edge of said opening having a depending lip formed by the stock of said web and adapted to be bent against the upper side of the last mentioned reenforcing rod.

7. A chair for supporting a concrete reinforcing rod comprising a horizontal flat base, and a standard of channel form in horizontal section rising from said base and having a lip struck out of its web which projects upwardly and is adapted to form a seat for a rod and to be bent with its upper

end against the same for confining it thereon, the opening formed in said web by the deflection of the stock of said lip being adapted to receive a reenforcing rod arranged at right angles to the first mentioned rod, and the parts of said flanges adjacent to said lip being adapted to bend against the last mentioned rod.

8. A chair for supporting concrete reenforcing rods comprising a flat horizontal base adapted to rest on a foundation, a standard of channel shape in horizontal section rising from said base and having upper and lower retaining means for supporting two pairs of cross rods, the members of one pair being arranged above the members of the other pair, said channel shape standard having an upright web and upright flangs projecting inwardly from opposite upright edges of said web, said lower retaining means comprising an upwardly projecting lower lip struck out of the lower part of said web and forming a seat for the lower rod of the lower pair and the upper end of said lower lip being adapted to be bent against said lower rod of the lower pair

75 for holding the same on said seat, and the opening formed in the web by the deflection of the stock thereof to form the lower lip being adapted to receive the upper rod of the lower pair, and the upper edge of said 80 opening having a depending lip formed by the stock of said web and adapted to be bent against the upper side of the upper rod of the lower pair, and said upper retaining means comprising an upwardly projecting lip struck out of said web and adapted to form a seat for the lower rod of the upper pair and to be bent against the latter, and the opening formed in said web by the deflection therefrom of the stock of said 85 last mentioned lip, which opening is adapted to receive the upper rod of the upper pair, and the upper ends of said flanges adapted to be bent against the upper rod of the upper pair for holding the same in place.
